UNITED STATES PATENT OFFICE.

ERNST G. K. ANDERSON, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

1,312,380.

Specification of Letters Patent.

Patented Aug. 5, 1919.

Application filed March 7, 1914. Serial No. 823,237.

To all whom it may concern:

Be it known that I, ERNST G. K. ANDERSON, a citizen of the United States, residing at Chicago, in the county of Cook and State of Illinois, have invented new and useful Improvements in Electric Switches, of which the following is a full, clear, concise, and exact description, reference being had to the accompanying drawing, forming a part of this specification.

My invention relates to mechanical cut-outs for electric circuits, and has for one of its objects an improved construction of snap switches both for wall and pendant switches.

For the purpose of disclosing my invention I have illustrated certain embodiments thereof in the accompanying drawings, in which—

Figure 1 is a longitudinal sectional view 20 of a wall switch embodying my invention;

Fig. 2 is a sectional view taken on the line 2—2 of Fig. 1;

Fig. 3 is a disassociated perspective view 25 of the movable switch blade and its operating parts;

Fig. 4 is a longitudinal sectional view of a pendant switch embodying my invention, taken on the line 4—4 of Fig. 5;

Fig. 5 is a sectional view taken on the 30 line 5—5 of Fig. 4;

Fig. 6 is a top plan view with the inclosing casing or shell removed;

Fig. 7 is a sectional view on the line 7—7 35 of Fig. 4; and

Fig. 8 is a perspective view of the push-button bar.

In the structure disclosed in Figs. 1 to 3, inclusive, I provide a suitable casing 10, which may be of insulating or other suitable 40 material as desired, which casing is adapted to fit within the wall and is provided at its front with a flange 11 to which is attached the front cover plate 12. Mounted within this casing is a pair of spring contacts 13 and 14, each provided with a suitable binding screw 15 by which the leading-in wires may be connected to the contacts. The circuit is closed between these spring contact fingers by a switch blade 16, which is adapted 45 to be snapped between the fingers and engage each of the same to thereby close the circuit. The rear end of this switch blade

is pivoted upon a post 17 and is provided with a rearwardly extending projection 18. Also mounted on the post 17 is a rocking 55 frame 19 provided with a pair of downwardly extending lugs 20 between which the rear projection 18 is adapted to pass. The lugs 20 are spaced apart a sufficient distance to permit of some lost motion of the frame 60 19 with respect to the rearwardly extending projection 18 as clearly shown in dotted lines in Fig. 1. The rocking frame is provided with a pair of laterally extending 65 arms 21, having slots 22 formed therein in which are fastened the pins of the push-buttons 23 and 24. The blade 16 is provided at its front end with a cylindrical casing 25 in which is adapted to be fitted a coiled 70 spring 26. The opposite end of this coiled spring fits within and bears upon a hollow plunger 27, the closed end of which is cone-shaped and has adapted to bear thereon one 75 end of a pin 29. The opposite end of this pin is pivotally secured, as at 30, in an up-turned lug 31 on the locking frame. The lug 31 is off center from the pivot 17, so that when this lug is moved to a position to align the pin with the pivot point the spring 26 will be compressed, and after the switch 80 blade has been moved past the point or center the expansion of the spring will cause the blade to snap in one direction or the other.

In operation, assuming the parts to be in 85 the position shown in Fig. 1 with the circuit closed, when pressure is applied to the button 24 the rocking frame 19 is rocked to move the lugs 20 and the lug 31 downwardly. As the lug 31 moves downwardly 90 carrying with it the pivoted end of the pin 29 the pin 29 will compress the spring 26 and will also exert a force on the spring. It will have a component tending to move the spring upwardly due to the angle which the 95 pin 29 assumes with respect to the switch blade. As the downward movement of the lug 31 continues the compression of the spring increases and also the upward component of the force increases until sufficient 100 force is exerted to overcome the initial friction between the switch blade 16 and the contacts 13 and 14. As soon as this initial friction is overcome the blade 16 will snap

upwardly to the dotted line position shown in Fig. 1. It will be noted, however, that the movement of the switch blade 16 does not depend entirely upon the coiled spring 26, but in case the force exerted by the pin 29 is not sufficient to overcome the initial friction between the blade 16 and the contacts 13 and 14 this blade will be positively moved by the engagement of the lugs 20 with the projection 18, the coiled spring 26 being depended upon only for the purpose of producing a snap action of the blade.

In the structure illustrated in Figs. 4 to 8 I have shown a modification of my snap switch adapted particularly for pendant switches. In this structure I have illustrated the pendant switch as comprising a cylindrical insulating casing 32 which is surrounded by an inclosing metallic casing 33. The spring contact fingers 34 are mounted in the upper end of the casing 32 and are provided with suitable binding posts 35, to which the leading-in wires may be connected. Circuit is closed between the contact fingers by means of the movable switch blade 16, which in this structure is pivoted upon a cross pin 36 secured in the insulating casing 32. This switch blade is of substantially the same construction as shown in Figs. 1, 2 and 3, except that the rearward extension 18 is provided with an upturned lug 37 adapted to pass between the two lugs 38 on the push-button bar 39. The pin or arm 29 at its rear end is pivotally connected, as at 40, with the push-button arm 39. The operation of this structure is substantially the same as that illustrated in Figs. 1, 2 and 3. With the parts in the position illustrated, when one end of the push-button arm is pressed the pin 29 will be brought into alignment with the pivot point of the blade and the spring 27 compressed. After the push-button bar has been moved sufficiently far for the arm 29 to have passed its dead center, then the snap action will occur, due to the expansion of the spring 27. In this modification, as the form shown in Figs. 1, 2 and 3, a lost motion connection must be provided between the push button and the switch blade. As shown in Fig. 4 the lugs 38 are spaced apart sufficiently to allow the pivotal connection 40 to pass the dead center before the lug 38 engages the lug 37 to move the switch blade positively. A corresponding movement from the other side of the push button arm 39 will cause the blade to move to close the circuit.

Having thus described my invention, what I claim as new and desire to secure by Letters Patent is—

1. In an electric switch, the combination with a stationary contact, of a pivoted switch blade coöperating with said contact, a spring carried bodily by said blade and

having a definite line of action with respect thereto, a movable operating member, and means for transmitting pressure from said operating member to said spring comprising a member pivoted to said operating member at a point movable from one side to the other of a plane through the axis of the blade and the point of application of pressure to the spring.

2. In an electric switch, the combination with a stationary contact, of a pivoted switch blade coöperating with said contact, yielding means carried bodily by said blade and having a line of action fixed with respect to said blade, and means for actuating said yielding means comprising an operating member and a pin pivoted thereto and exerting pressure on said yielding means.

3. In an electric switch, the combination with a stationary contact, of a pivoted switch blade coöperating with said contact, a helical spring carried bodily by said blade and having its axis substantially in a plane through the axis of the blade, and movable means for actuating said spring, said means comprising an operating member, and a pin pivoted thereto and exerting pressure on said spring.

4. In an electric switch, the combination with a stationary contact, of a pivoted switch blade coöperating with said contact, a helical spring carried bodily by said blade and having a definite line of action with respect to said blade, movable means for actuating said spring, said means comprising an operating member and a pin pivoted thereto, and a lost motion connection between said operating member and said blade.

5. In an electric switch, the combination with a stationary contact, of a pivoted switch blade coöperating with said contact, a spring carried bodily by said blade and having a definite line of action with respect thereto, a movable operating member, and means for transmitting pressure from said operating member to said spring comprising a member pivoted to said operating member at a point movable from one side to the other of a plane through the axis of the blade and the point of application of pressure to the spring, and a lost motion connection between said operating member and blade.

6. An electric switch comprising a base, a fixed contact, a movable contact, a movable operating member for said movable contact, supported by said base, a spring for said movable contact mounted to swing about a fixed pivot, and a rigid member pivotally connected to said spring and having a portion directly pivoted to and movable with said operating member.

7. An electric switch comprising a base, a fixed contact, a movable contact and a

movable reciprocating member for said movable contact, supported by said base, a spring for said movable contact mounted to swing about a fixed pivot, and a rigid member pivotally connected to said spring and having a portion directly pivoted to and movable with said reciprocating member.

Copies of this patent may be obtained for five cents each, by addressing the "Commissioner of Patents, Washington, D. C."

In witness whereof, I have hereunto subscribed my name in the presence of two witnesses.

ERNST G. K. ANDERSON.
